ISAAC CHURCH, JR., OF NORWALK, CONNECTICUT.

Letters Patent No. 79,204, dated June 23 1868.

IMPROVEMENT IN OPERATING SLIDE-VALVES.

The Schedule referred to in these Letters Patent and making part of the same.

TO ALL WHOM IT MAY CONCERN:

Be it known that I, ISAAC CHURCH, Jr., of Norwalk, in the county of Fairfield, and State of Connecticut, have invented a new and useful Improvement in Operating the Slide-Valves of Steam-Engines and Pumps, of which the following is a full, clear, and exact description, reference being had to the accompanying drawing, forming part of this specification, and in which—

Figures 1 and 2 represent longitudinal sectional elevations of a steam-cylinder and piston, with valve or valves connected therewith, embracing my improvement, and showing the working parts in different positions.

Similar letters of reference indicate corresponding parts.

This, my improvement, is applicable, among other purposes, to direct double-acting steam-pumps, and it will suffice here to regard the same in such connection. Said improvement is based upon that principle of action, which has before been applied in various forms, in which the valve controlling the action of the piston is shot or worked alternately in opposite directions by steam admitted through the agency of secondary valves that are opened and closed by the motion of the piston; but this, my invention, differs from previous devices of the character referred to in causing the main valve to be thrown or shot by steam admitted through puppet-valves, so arranged as that the engine-piston operates in a direct manner upon their stems to lift, and, it may be, also, to drop them; and whereby not only are all outside connections for operating the valves dispensed with, but a most simple and efficient interior valve-operating action or arrangement secured.

Referring to the accompanying drawing, A represents the main or working-cylinder, and B the reciprocating piston therein, with its rod C. The piston B it is preferred to make with bevelled or curved edges, to facilitate the lifting of the puppet-valves, as hereinafter described, but this may, to a greater or lesser extent, be dispensed with, by suitably bevelling or shaping the ends of the stems to the puppet-valves. D is the main slide-valve, of a piston-shaped character or construction, hung free to reciprocate in a cylinder, E, and formed with heads or partitions, a' and b', leaving spaces c, c', and d between them. F F' are steam-ports or passages, connecting the valve-cylinder E near its centre with the ends or adjoining portions of the main cylinder. G is the steam-inlet pipe to the valve-box or chamber, the same opening into a passage, H, which communicates, by openings e e' and f f', with the valve-cylinder E.

I I' are puppet-valves to the openings e e'. These valves are provided with stems g g', which project down at their ends or points into the working-cylinder A.

J is an exhaust-cavity, made in the cylinder E, at or near its centre, and communicating with an exhaust-pipe or passage, J', which has branching from it passages h h', terminating in contracted openings i i' to the cylinder E, near opposite ends of it.

Having thus described how the several working-parts are or may be constructed and arranged, it will suffice here briefly to refer to the operation, which is as follows:

Supposing the parts to be in the position represented in fig. 1 of the drawing, then the piston B, which, in arriving at such position, has lifted the puppet-valve I' by its stem g', is ready to receive steam on the back of it to propel it in the opposite direction, the puppet-valve I', in being thus opened, having admitted steam through the opening e', so as to throw the main valve D to the left; said valve, after it has been started, being checked in its throw, by the steam admitted to the cylinder E in rear of the valve gradually escaping by the contracted aperture i' and passage h' to the exhaust-outlet J', or said valve may be otherwise checked or cushioned. This throw or change in position of the valve D opens the cylinder-port or passage F' through the space or cavity c' of the valve, opening f', and passage H to the inlet-pipe G, and at the same time opens the passage F through the cavity or space d of the valve to the exhaust-cavity J and outlet J', which reverses the action of the piston B, causing it to move to the position it is shown approximating by arrow in fig. 2, where it is represented as having nearly reached the opposite end of the cylinder, and as about or nearly so to lift the puppet-valve I, in order to admit steam, by the opening e, to the opposite end of the valve, for the purpose of throwing it in the reverse direction, and thereby admitting steam, by the passage F, cavity c, and opening f, to the opposite end of the piston B, and opening the cylinder A to the exhaust-outlet J' by the passage F', valve-space d, and cavity

J, the main valve, it may be, being similarly checked in its throw by escape of steam through the contracted aperture i and passage h , as it was in moving in the opposite direction by the passage h' and aperture i' .

Thus it will be seen that not only are all the working parts which control the motion of the main valve boxed in or enclosed, thereby doing away with outside connection and leakage through stuffing-boxes, but valve-gear of any description is dispensed with, and the piston, by its direct action or lift on the puppet-valves, alternately at opposite ends, made to operate the main valve, so as to reverse the action of the engine, and keep up a continuous reciprocating movement. The puppet-valves close of their own weight after the piston has passed them, or they may be shut by springs or by extraneous weight or pressure, as desired.

I do not claim broadly operating the valves, which admit steam to throw the main valve, by means of the piston of the engine; but

What I claim as new, and desire to secure by Letters Patent, is—

The arrangement of the puppet-valves I I' with relation to main valve D, steam-passage H, and piston B, in such manner as to dispense with all outer connection therewith, substantially as shown and described.

ISAAC CHURCH, JR.
